Primary Examiner — Omeed Agilee(74) *Attorney, Agent, or Firm* — Barnes & Thornburg LLP(57) **CLAIM**

The ornamental design for a pad for surgical boot, as shown and described.

DESCRIPTION

FIG. 1 is an isometric view of a pad for surgical boot in accordance with our design;

FIG. 2 is a top plan view of the pad for surgical boot of FIG. 1;

FIG. 3 is a bottom plan view of the pad for surgical boot of FIG. 1;

FIG. 4 is a first side elevation view of the pad for surgical boot of FIG. 1;

FIG. 5 is a second side elevation view of the pad for surgical boot of FIG. 1;

FIG. 6 is a first end elevation view of the pad for surgical boot of FIG. 1;

FIG. 7 is a second end elevation view of the pad for surgical boot of FIG. 1; and,

FIG. 8 is an isometric view shoring the pad for surgical boot of FIG. 1 attached to a surgical boot (in dotted line) of a surgical stirrup (in dotted line).

The broken lines depict portions of the pad for surgical boot that form no part of the claimed design.

1 Claim, 6 Drawing Sheets(56)
